TENNIS RACKET VISE

Harold W. Roberts, Riverside, Ill., assignor to
Thompson Mfg. Co., Chicago, Ill.

Application August 23, 1933, Serial No. 686,389

5 Claims. (Cl. 273—73)

This invention relates to improvements in tennis racket vises, and the objects of the invention are to provide means for holding the racket in such a manner that undue distortion is prevented; to clamp the racket so that the periphery of the racket is unobstructed for the insertion of the awls which are used to hold each string as it is tensioned, and so that there is free space for working with the hands underneath the frame from all sides in weaving in the cross strings.

Another object is to provide a portable vise suitable for restringing the rackets, and to provide a portable vise with which a string puller may be used for pulling the strings and measuring the tension so that the restringing is greatly facilitated, and uniform results may be obtained by inexperienced operators.

Other objects and advantages will become apparent in the following description, taken with reference to the accompanying drawings.

Fig. 1 is a plan view of a preferred form of a tennis racket vise embodying my invention.

Fig. 2 is a vertical section on the line 2—2 of Fig. 1.

Fig. 3 is a partial plan section on the line 3—3 of Fig. 2.

Fig. 4 is a detail section taken on the line 4—4 of Fig. 3.

Fig. 5 is a face view of the puller handle showing the tension indicating dial.

Fig. 6 is a plan view of a modified form of the vise.

Fig. 7 is a section on the line 7—7 of Fig. 6.

Fig. 8 is a section on the line 8—8 of Fig. 6.

Fig. 9 is a plan view of a second modified form of vise and puller.

Fig. 10 is a sectional elevation taken on the line 10—10 of Fig. 9.

Fig. 11 is a detail view of the puller shown in Fig. 9, with portions of the casing broken away.

Fig. 12 is a section taken on the line 12—12 of Fig. 11.

In the preferred form, the vise 14 is rotatably mounted on a circular base 15 which may be secured to a bench or other support by bolts 16. The vise is pivoted on a central stud 17 fixedly secured in the base, and a nut 18, threaded on the stud, is provided for locking the vise in rotative positions.

The vise 14 comprises a circular base portion 19 on which are cast four upwardly projecting arms 20, arranged at right angles to each other, and on the upper ends of the arms are mounted a fixed clamp finger 21 for engaging in the base 55 of the frame, and three movable clamp fingers 22 for engaging in the sides and end of the frame. The clamp 21 is secured to the rear arm by a bolt 23, and the clamps 24 are secured to their respective arms by horizontally disposed 55 bolts 25 which extend rotatably through a down-

wardly projecting lug 26, formed on the outer end of the foot 27 of the clamp and through the upper end of the arm 20. The bolt 25 is shouldered at 28 to abut against the outer surface of the arm, and the inner end of the bolt threads through a downwardly projecting lug 29 formed on the inner end of the foot 27. Thus the clamps 24 rest solidly on the upper ends of the arms, and are guided horizontally as they are drawn outwardly by rotating the adjusting 10 screws 25.

The vise arms 20 are from five to six inches in length so that the space underneath the racket is unobstructed for the hands of the operator in lacing in the cross strings and the operator may work from any side of the frame. This construction also leaves the outer surface of the racket frame accessible for the insertion of the awls for holding the tension of the strings as the work progresses.

For pulling the strings and determining the tension, I provide means for mounting a puller 30 directly on the vise instead of on the base as has formerly been the practice, so that the strain in pulling the strings does not pass through the center bolt 17 and tend to rotate and tip the vise. Around the lower portion of the vise 14 is a rail 31, cast integrally with the vise, and the puller 30 has a foot 32 having hooks 33 for engaging under the lower edge of the rail. A latch 34 is pivotally mounted on the puller for gripping the angular upper edge of the rail to hold the puller in position. The latch is urged downwardly by a spring 35, and it has a thumb piece 36 so that the puller may be readily engaged and disengaged in any position around the frame of the racket.

On the foot 32 is cast a bracket 38 in which is rotatably mounted a horizontally disposed shaft 39. On one end of the shaft is pinned a 40 drum 40, which may have a rubber facing 41 for winding the strings; and on the opposite end of the shaft are rotatably mounted a shell 42 and a flanged member 43 which is rigidly connected to the shaft by a pin 44 which is inserted through 45 suitable apertures 45 in the shell 42. The shell and flange member are yieldably connected by a double coiled spring 46 having a central loop 47 in which the end of the pin 44 is engaged, thus connecting the one end of the spring to 50 the shaft 39. The straight ends 48 of the spring are hooked into the shell 42, as best shown in Fig. 4.

On the inner end of the shell 42 is pinned a ratchet wheel 50 which is engaged by a gravity 55 operated pawl 51 to hold the shell 42. The pawl 51 is pivotally mounted on the side of the bracket 38 and has a tail piece 52 for urging the pawl into contact with the ratchet wheel, which also serves as a thumb piece for disengaging the pawl. 60

An index finger 53 is fixed to the outer edge of the shell 42, and the finger projects over the face of the member 43 into co-operable relation with the dial 54 marked thereon, and normally the finger 53 is in contact with a stop pin 55 fixed in the face of the member 43, with very little tension in the spring 46.

In operation, the puller 30 is clamped in position on the rail 31 adjacent the hole through which the next string is to be threaded. The string is then drawn through the hole and attached to the drum, the drum being below the frame of the racket so that the string will be pulled downwardly at an angle so that the awl can be inserted. The shell or handle 42 is then grasped with one hand and rotated clockwise, as viewed in Fig. 2. As the string is being tightened up the shaft and shell will rotate together with the finger 53 in contact with the stop pin, and continue to move together an indefinite amount until the string is tight. Then further rotation of the shell winds the spring 42, and the amount of relative movement between the shaft and the shell is indicated on the dial 54 which is marked to show the pull on the string in pounds. The spring is designed to give the maximum desired tension in less than one turn and before the finger 53 strikes the opposite side of the pin 55. This avoids the necessity of counting the number of times the shell is rotated and thus avoids confusion. Backward movement of the shell is stopped by the pawl 51; and when the desired tension is obtained the awl is forced into the string hole. The pawl is then released and the string detached. To pull the next string, from the opposite side of the frame, the puller may be shifted around on the rail, or the puller may be taken off and held while the vise is rotated.

40 In the form shown in Figs. 6, 7, and 8, the vise comprises a flat annular head 56 which is supported on two legs 57 from a suitable base 57'. The head is provided with a billiard 58 and clamps 59 for mounting the racket 60 on the upper side 45 thereof, and around the outer edge of the head is a circular flange 61 on which are slidably mounted two pullers 62 for pulling the strings from opposite sides of the head. The pullers may be geared, as shown, and comprise a bracket 63 which hooks over the flange and has two spaced hooks 64 which engage in an undercut ring 65 formed on the under side of the head, so that the pullers are shiftable around on the flange, and are held in place by friction when 50 a string is being pulled. A drum 66 is keyed to a vertical shaft 67 which extends rotatably through the bracket 63, and on the lower end of the shaft are keyed a ratchet wheel 68 and a spur gear 69. In the bracket and spaced inwardly from the shaft 67 is fixedly secured a stud shaft 70, on which is rotatably mounted a disc 71, having a pinion 72 secured thereto which meshes with the gear 69. A shell 73 which serves as a handle is rotatably mounted on the shaft 70 in cooperative relation with the disc 71. A pin 74 is inserted through an aperture 75 in the shell, through the hub 76 of the disc and into a circumferential groove 77 in the shaft 70, for holding the disc in position; and the disc is connected to the shell by a double coil spring 78 which loops over the pin 74, and has its outer ends 79 hooked into the shell 73.

In the modification shown in Figs. 9, 10, 11 and 12, the vise 80 consists of an inverted spider, with four arms, 801 which project outwardly and upwardly from a relatively small base 802 so that the space under the vise is accessible 5 from all sides. On the upper ends of the arms, clamps 81, 82, 83, and 84 are mounted for gripping the racket frame internally. For mounting a puller I provide a round rail 85 on which a hand puller is loosely fulcrumed. This form 10 of puller comprises a flanged disc 86 which is notched into the center of its hub 87, and has a handle 88 formed thereon. On the disc 86 is rotatably mounted an angular ring shaped shell 89 which is notched in conformity with the disc 15 86, and encloses a space in which is contained a curved helical spring 90 which is compressed between a lug 94 formed in the shell, and a lug 92 in the member 86. On the outer surface of the shell 89 are provided beackets 95, 96 to which the 20 string is attached. In this form, the vise may be pivoted directly to the bench or table by a bolt 97.

Having thus described my invention, I claim:

1. A tennis racket vise having means for rigidly clamping the racket, a rail extending around the vise below the level of a racket therein, a string puller slidably mounted directly on the rail and movable to different positions about the periphery of a racket, and having a yieldable latch to engage the rail and the string puller being positioned close to and below a racket to offer no obstruction to the stringing operation.

2. In combination, a tennis racket vise having a rail larger than a racket extending around and below the vise, a string puller having a hook for engaging the under side of the rail, and a yieldable latch mounted on the puller for engaging the upper side of the rail so that the puller may be readily shifted along the rail.

3. In combination, a tennis racket vise having upwardly extending arms for internally engaging and mounting a racket, a continuous rail extending below and outwardly beyond a racket 45 leaving a free working space around and under a racket frame, and a string puller slidably mounted on the rail and having a latched portion yieldably engaged therewith and shiftable to different positions around a racket frame. 50

4. A tennis racket vise comprising a base, a vise rotatable on the base and having upwardly and inwardly extending arms and clamping members for gripping the frame of a racket internally, leaving a free working space around and under a racket frame therein, a rail carried by the vise extending around outside of and below a racket in the frame, a string puller mounted to slide on the rail and having a yieldable latch engaging the rail and the upper portion of the 60 string puller being below the level of a racket frame in the vise to permit free access thereto.

5. In a tennis racket vise, means for rigidly clamping a racket frame, a rail extending below the vise, a string puller having a hook to engage 65 the under side of the rail, a spring pressed latch mounted on the puller to yieldingly engage the upper side of the rail, and a thumb piece on the latch in position to be readily engaged by an operator to release the latch for slidably moving the puller along the rail.

HAROLD W. ROBERTS.
